AIR TRANSLATING APPARATUS

Gustav H. Koch, Springfield, Mass., assignor to Westinghouse Electric & Manufacturing Company, East Pittsburgh, Pa., a corporation of Pennsylvania

Application January 31, 1942, Serial No. 429,015.

2 Claims. (Cl. 248—126)

This invention relates to an electric fan, and particularly to an electric fan adapted to be mounted on a substantially vertical support, such as a wall, or supported upon a substantially horizontal surface, such as a desk.

An object is to provide improved apparatus of the character set forth.

Heretofore, fans have been provided which may be mounted on a substantially vertical wall by means of a screw passing through the front or upper surface of the fan base and engaging the wall, or supported on a substantially horizontal surface, such as a desk. This arrangement provides a substantial mounting, but it is objectionable to a certain extent because of the unsightly appearance of the screw head when the fan is mounted on a wall, and the unsightly appearance of the screw hole when the fan is used on a desk or other horizontal surface. Accordingly, it is an object of this invention to provide a fan that may be mounted on a substantially vertical support by means of a screw, or the like, passing through the base of the fan, or used on a substantially horizontal support, such as a desk, wherein these objections are eliminated.

A further object is to provide a fan of the character set forth including means for mounting the same on a wall and a decorative cover for the mounting means.

A still further object is to provide a fan of the character set forth having a recess therein for mounting the same on a wall and a cover for the recess which is readily accessible from the exterior of the fan for attaching or removing the same.

A still further object is to provide a fan including means for mounting the same on a wall and a cover for the mounting means which may be readily attached or removed from the fan from the exterior thereof, whereby the means for attaching the cover to the fan are not visible from the exterior of the fan.

These and other objects are effected by my invention as will be apparent from the following description and claims taken in accordance with the accompanying drawing, forming a part of this application, in which:

Fig. 1 is a side elevation, with parts broken away, of a fan embodying this invention shown resting on a horizontal surface;

Fig. 2 is a side elevation thereof showing the fan mounted on a substantially vertical wall;

Fig. 3 is an enlarged fragmentary top plan

view showing the cover for the mounting means in position on the fan support;

Fig. 4 is an enlarged fragmentary top plan view of the fan support, with the cover for the mounting means removed;

Fig. 5 is a view of the fan support and cover for the mounting means as seen substantially along line V—V of Fig. 1; and,

Figs. 6 and 7 are sections taken along lines VI—VI and VII—VII, respectively, of Fig. 1.

Referring now to the drawing more in detail, in Figs. 1 and 2, an electric fan embodying this invention is shown. The fan includes a hollow base or support member 11 having an arm or standard 12 extending therefrom, a motor housing 13 in which the motor parts are mounted, a set of fan blades 16 which are rotated by the motor, and a fan guard 17 which is attached to the motor housing. The upper end of the standard 12 is bifurcated to receive one end of a bracket 18, the other end of which is attached to the motor housing 13. The motor housing, the fan blades, and the guard are attached to the standard 12 by a bolt 19 that passes through the bifurcated ends of the standard 12 and the bracket 18, and a wing nut 20 which screw threads on the bolt 19 to clamp the bifurcated ends of the standard 12 and the bracket 18 together with sufficient pressure to prevent the assembly including the motor, the fan blades, and the guard from tipping downward by gravity.

The base or support 11 is a thin walled hollow member, formed by die casting or any other suitable means. The arm or standard 12 may be formed integral with the base member or attached thereto by any suitable means. The bottom of the base member 11 is closed by a flat plate 22 which provides a large contact area on which the fan rests when placed on a horizontal surface, as shown in Fig. 1. The plate 22 may be held in position by any suitable means, such as screws or peening over the edge of the base member 11.

When the fan is mounted on a substantially vertical wall 24, such as a wall of a room, as shown in Fig. 2, the flat bottom is positioned against the wall 24. As seen from the drawing, when the fan is mounted on the wall 24, the base member 11 is reversed or turned 180° in relation to the motor housing from its position when the fan is resting on a horizontal surface. This is done by removing the wing nut 20 and the bolt 19, then turning the base 180° with respect to the motor housing, and then replacing the bolt 19 and the wing nut 20.

The top wall of the base member 11, indicated generally by the reference character 25, extends upwardly and rearwardly from the front edge of the base 11, as seen in Fig. 1. As indicated at 27, Figs. 1, 2, and 4, a portion of the top wall 25 is depressed or countersunk. This portion of the wall 25 is ichthyoidal-shaped and has a first aperture 29 and a second aperture 30 therein. A cylindrical casing 31, defined by a cylindrical wall 32 and a bottom wall 34, surrounds the aperture 30 on the under side of the top wall 25 and depends from the top wall. The bottom wall 34 is substantially parallel to the plate 22 that closes the bottom of the base and it has an aperture 36 therein which is substantially co-axial with an aperture 37 in the plate 22.

To mount the fan on the substantially vertical wall 24, the fan is positioned, as shown in Fig. 2, with the plate 22 against the wall, and a screw 38 is inserted through the apertures 36 and 37 and screwed into the wall 24 far enough to hold the plate 22 tight thereagainst. As seen from Fig. 2, the head of the screw does not project beyond the top wall 25 of the base member 11.

An ichthyoidal-shaped decorative cover member 40, slightly smaller than the depressed portion 27 of the top wall 25 of the base member 11, is provided for covering the apertures 29 and 30 and the head of the screw 38. This cover conforms to the general curved shape of the wall 25, and it has a substantially normal flange 41 formed along its peripheral edge, except as indicated at 42, Figs. 1, 2, and 3, the flange being left off this portion so that a tool may be inserted between the cover 40 and the base member 11 at this point to remove the cover. This flange is slightly deeper than the depressed or countersunk portion 27 of the top wall 25 of the base member so that when the cover is placed in position over the apertures 29 and 30 it extends slightly above the top wall 25 of the base member 11 and thus adds to the aesthetic qualities of the fan. A pair of resilient fingers 43 are formed integral with the cover 40, on opposite sides thereof. These fingers are bent outwardly intermediate the ends thereof to form ridges 44 therein which project beyond the peripheral edges of the cover 40.

To place the cover 40 in position, it is placed in the depressed or countersunk portion 27 in the top wall 25 of the base member 11 with the fingers 43 lined up with the aperture 29 in the top wall 25. When so positioned the ridges 44 will contact the wall 25 adjacent opposite sides of the aperture 29 and prevent the cover 40 from assuming a position, such as shown in Figs. 1 and 2. However, the fingers 43 are resilient and a slight force applied to the top of the cover 40 will cause the fingers to be sprung toward each other by reason of the ridges 44 bearing against the top wall 25

of the base member 11 adjacent the aperture 29, and the ridges 44 will snap through the aperture 29 and engage the under side of the top wall 25 of the base member 11 adjacent the aperture 29, as shown in Fig. 5, and retain the cover 40 in position over the aperture 29.

The cover 40 may be easily snapped off by applying a slight force at 42 with one's finger nail or some flat tool such as a pen knife or screwdriver.

From the foregoing description, taken in connection with the drawing, it is seen that this invention provides a fan including an improved arrangement for mounting it on a substantially vertical support or wall and an improved, economical, decorative cover for the mounting means that may be readily applied or removed from the fan from the exterior thereof. This invention provides, also, a cover for the mounting means that may be attached to the fan without the use of fastening means visible from the exterior of the fan.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In an electric fan or the like, a supporting pedestal having a flat bottom and a curved top wall sloping to a junction with said flat bottom, fastening means extending through an opening in said pedestal for engaging an external support, a cover for concealing said opening and said fastening means, spring clips carried by said cover and engaging said pedestal for removably retaining said cover in position, a portion of the lower edge of said cover being spaced from the corresponding portion of said flat bottom to provide a normally invisible opening for the reception of means for disengaging said cover.

2. In an electric fan or the like, a pedestal including a base having a flat bottom and a curved top wall, there being a depressed portion disposed near one end of said top wall and forming a seat, fastening means extending through a hole in said depressed portion to engage an external support, a removable cover adapted to engage said seat for concealing said depressed portion, said hole and said fastening means, and spring clips depending from said cover and engaging the walls of an opening in said top wall for removably retaining said cover in position, there being an opening formed at the junction of said cover and said base affording access for means for disengaging said cover.

GUSTAV H. KOCH.
